[57] CLAIM

The ornamental design for a bandage backing, as shown and described.

DESCRIPTION

FIG. 1 is a perspective view of bandage backing showing the new design;

FIG. 2 is a top plan view thereof;

FIG. 3 is a bottom plan view thereof;

FIG. 4 is a side elevational view thereof, the opposite side elevational view being identical thereto;

FIG. 5 is an end elevational view thereof; the opposite end elevational view being identical thereto;

FIG. 6 is a perspective view of an alternate embodiment of the invention;

FIG. 7 is a top plan view of the embodiment shown in FIG. 6;

FIG. 8 is a bottom plan view of the embodiment shown in FIG. 6;

FIG. 9 is a side elevational view of the embodiment shown in FIG. 6, the opposite side elevational view being identical thereto;

FIG. 10 is an end elevational view of the embodiment shown in FIG. 6, the opposite end elevational view being identical thereto.

The broken lines in the drawing are for illustrative purposes only and do not form a part of the claimed design.
